UNITED STATES PATENT OFFICE.

NIELS A. CHRISTENSEN, OF MILWAUKEE, WISCONSIN.

INTERNAL-COMBUSTION ENGINE.

1,253,669.

Specification of Letters Patent. Patented Jan. 15, 1918.

Application filed December 8, 1913. Serial No. 805,287.

To all whom it may concern:

Be it known that I, NIELS A. CHRISTENSEN, citizen of the United States, residing at Milwaukee, in the county of Milwaukee and State of Wisconsin, have invented certain new and useful Improvements in Internal-Combustion Engines, of which the following is a specification, reference being had to the accompanying drawing, forming a part thereof.

This invention relates to starting apparatus of the type shown and described in my application Serial No. 630,630, filed June 1, 1911, comprising the usual ignition system, a compressor, a reservoir for the compressed starting fluid, means for carbureting the starting fluid, a distributing valve for admitting the compressed fluid into the engine cylinder on the firing strokes of the piston, an outwardly closing check valve in the connection between the cylinder and the distributing valve, and a driver's valve controlling the connections of the compressor and distributing valve with the reservoir.

The main objects of the present invention are to group the distributing valve and the compressor with a carburetor in a compact self-contained unit in which the distributing valve and the compressor have a common driving connection, thereby facilitating the application of the apparatus to cars and engines of different makes; to insure a rich or thoroughly carbureted initial compressed fluid charge for starting the engine; and generally to simplify and improve the construction and operation of starting apparatus of this class.

It consists in the construction, arrangement and combination of parts as hereininafter particularly described and pointed out in the claims.

In the accompanying drawing like characters designate the same parts in the several figures.

Figure 1 is a plan or top view of unitary starting apparatus embodying the invention; Fig. 2 is a front or side elevation thereof; Fig. 3 is a vertical longitudinal section on the line 3—3, Fig. 1; Fig. 4 is a similar section on the line 4—4, Fig. 1; Fig. 5 is a vertical cross section on the line 5—5, Figs. 1, 2 and 4; Fig. 6 is a cross section on the line 6—6, Figs. 1 and 7; Fig. 7 is a horizon-

tal section on the line 7—7, Figs. 2 and 5; Fig. 8 is a vertical cross section on the line 8—8, Fig. 1; Fig. 9 is a vertical section on the line 9—9, Fig. 1; and Fig. 10 is a section similar to Fig. 3, but in a plane at right angles thereto, looking toward the carburetor chamber, of a modification of the compressor controller.

The apparatus comprises a compressor *a*, the crank *b* of which may be connected manually or by an automatic controller, as shown in Fig. 4, with a driving shaft *c*, which has a bearing sleeve *d* in the carburetor casing *e*, and in turn may be connected with and driven by any convenient rotating part of the engine, such as the crank shaft.

To effect the manual and automatic control of the compressor, a rotary and reciprocating clutch member *f* is confined in the bearing *d*, between the crank *b* and the shaft *c*. This clutch member is provided at one end with a tongue *g*, which is in constant engagement with a cross slot in the end of the crank shaft, and at the other end it is provided with a shorter tongue *h*, which is adapted to be shifted into and out of engagement with a cross slot in the end of the shaft *c*. At each end beyond these tongues, the clutch member *f* is provided with a cylindrical guiding stem *i*, fitted to turn and movable lengthwise in axial bores in the adjacent ends of the crank shaft and shaft *c*. It is also formed with circular rack teeth meshing with a pinion *j* on a transverse shaft, which has bearings in the carburetor casing *e* and is provided with another pinion *k*, as shown in Figs. 3 and 4, and indicated by dotted lines in Fig. 5.

The pinion *k* engages, as shown in Fig. 3, with circular rack teeth on a plunger or piston *l*, fitted in a cylinder *m*, which is formed in the casing *e*. This plunger *l* is preferably made hollow, being open at one end and closed at the other end, with the exception of a leak passage *n*. The closed end of the plunger forming a piston head, is provided with a leather packing cup *o* secured thereto by a washer and a screw *p* threaded in the plunger and formed with the leak passage *n*.

The lower end of the screw is formed with an axial bore to receive a tube *q* projecting upwardly into the cylinder from the lower

head in which it is secured, and forming an extension of an air passage *r* in the cylinder wall, and it is adapted to rest on a lug on the lower cylinder head, forming a stop for limiting the downward movement of the plunger and preventing deformation and injury of the leather packing cup *o*. The tubular extension *q* and the cylinder wall form a well for oil or other suitable liquid, which will keep the leather packing cup pliable.

The cylinder *m* is provided at the end adjacent to the open end of the plunger with a port *s* and a packing ring or disk *t*, against which the open end of the plunger bears when it is shifted to start the compressor, thereby forming a fluid tight joint for a purpose hereinafter explained.

The port *s* communicates, as shown in Fig. 3, with a compressed air storage chamber *u*, in the carbureter casing *e*.

The pinion shaft is provided, as shown in Figs. 1 and 5, with a handle *v*, for manually operating the clutch member *f* and connecting the crank shaft of the compressor with the driving shaft *c*.

As in the apparatus covered by my former application, the discharge port of the compressor is connected by a pipe *w*, shown in Figs. 1 and 2, with a driver's or manually operated controlling valve (not shown), which controls its connection with a tank or reservoir (not shown) or with the atmosphere. A pipe *x* connects the passage *r* in the controller cylinder *m* with the pipe *w*, through a passage in the cylinder head outside the seat of the discharge valve, which is not shown, but is like or similar to that illustrated in my former application.

The distributing valve mechanism for controlling and properly timing the delivery of the compressed starting fluid to the engine cylinders, comprises a number, in the present case four, of radially movable valves *y*, guided and provided with seats in radial chambers of a casing *z*. The outer ends of the valve chambers are closed by caps 2, and springs 3, interposed between the caps and the valves tend to close the valves and to hold them against their seats. The valve chambers outside of the valve seats are connected by ports or passages 4, as shown in Figs. 6 and 7, with a cylinder or pressure chamber 5, with which the valve casing is formed or provided. The valve chambers are connected inside of the valve seats by passages or ports 6, shown in Fig. 5, and by pipes 7, shown in Figs. 1, 2 and 5, with the several engine cylinders (not shown). The cylinder or pressure chamber 5 is connected with the driver's valve and through it with the compressed air tank or the atmosphere, by a pipe 8, Figs. 2 and 9, and passages 9, 10, 11 and 12, formed respectively in the carbureter cover 13, casing *e*, distributer stand 14, casing *z* and cap 15.

A cam 16, by which the distributing valves *y* are actuated for starting the engine, is mounted and movable lengthwise on a square stem 17 which is threaded in the end of a shaft 18 axially therewith, as shown in Fig. 5. The shaft 18 is connected with the shaft *c* by spiral gears 19 and 20, and is provided with bearings in the carbureter casing *e* and in the distributer stand 14, which is formed as shown in Fig. 5, with a tubular stem fitted and secured in a socket in said casing. The stem 17 is secured in place by a jam nut 21, which when loosened will permit the stem to be turned in the shaft 18, thereby providing for angular adjustment of the cam to properly time the opening of the valves *y*.

A plunger or piston 22 is fitted in the chamber 5, coaxial with the stem 17 and shaft 18, and the hub of the cam 16, which projects outwardly beyond the stem 17, is provided with a spherical bearing engaging a hardened ball 23, mounted in the plunger in alignment with the axis of shaft 18. The cam with the piston is thrust upwardly and held normally out of operative relation to the inwardly projecting stems of the valves *y* by a spring 24, inserted between the outer end of the stem 17 and the outer end of the hub of the cam 16. The lower end of the cam is beveled or tapered lengthwise as shown in Fig. 5, so that when it is shifted by the plunger 22 into operative position, it will thrust whichever of the valve stems may be in its path, outward, and open the corresponding valve *y*, as shown in Fig. 7.

The lower end of the plunger 22, when it is thrust downwardly by the admission of compressed air or gas into the chamber 5 above the plunger, is pressed and held tightly against a seat or shoulder at the lower end of said chamber, thereby preventing the escape of the compressed starting fluid through the bearings of the valve stems and of the shaft 18. The plunger in its outer and normal position, closes the ports or passages 4, as shown in Fig. 6, and in its inner position opens said ports, establishing communication between them and the passage 12.

The carbureter comprises a chamber 25, formed in the casing *e*, and a float 26, guided and movable vertically upon a spray nozzle 27, threaded in the cover 13, as shown in Figs. 3, 8 and 9. The nozzle, which projects downwardly into the chamber 25 below the liquid level therein, opens at its upper end into the passage 9, and is provided at its lower end with a retaining ring 28 for holding the float thereon when the cover 13 is removed from the carbureter casing *e*.

To supply the chamber 25 with gasoline or other liquid fuel, the cover 13 is formed, as shown in Fig. 8, with a passage 29, terminating at its outer end in a cavity 30. A

recessed cap 31, in which a supply pipe 32 is threaded, is fastened to the cover 13 over the cavity 30, and a strainer 33 of chamois skin or other suitable material, is interposed 5 between said cap and cover, to filter the gasoline or other liquid fuel before it enters the carbureter chamber.

An upwardly or outwardly closing needle valve 34, guided and having a seat in the 10 passage 29 is operated by the float 26 to regulate the flow of gasoline or other liquid fuel into the chamber 25, and to maintain a substantially constant liquid level in said chamber. To limit the downward movement of 15 the valve 34, its stem is provided with a collar, which is adapted to rest upon a stop flange or collar on the nozzle 27, as shown in Fig. 8, when the valve is open. The passage 29 is provided with a check valve 35, which 20 closes outwardly, thus allowing pressure to be established and maintained in the chamber 25 while the starting apparatus is in operation.

As shown in Fig. 9, the vertical passage 10 25 in the carbureter casing *e*, forms a well which communicates near the bottom with the chamber 25, through a small opening or leak passage 37, thus allowing the gasoline or other liquid fuel to flow from said chamber into said well, and to fill it to the same 30 level. The tube 38, secured in the cover 13, with its upper end in communication with the passage 9, extends downwardly into the well 10 below the liquid level therein. An 35 enlargement at the end of the passage 9 in the carbureter cover 13, with which the compressed air supply pipe 8 connects, communicates directly through an opening or port 39 with the upper part of the chamber 25.

40 The shaft *c* has a reduced tapered extension 40 at one end projecting from the casing *e*, for the attachment of a gear, sprocket wheel or other driving member for connecting it with the crank shaft or other convenient rotating part of the engine, and it is 45 formed or provided adjacent to such extension, as shown in Fig. 4, with a collar 41, which is fitted in a recess formed therefor in the end of the casing *e*, and is confined therein by an annular cap or plate 42 bolted to the casing. The cap or plate 42 is formed on the inner side next to the collar 41 with an annular recess in which a packing washer 43 50 is inserted, to form a dust and oil tight joint.

55 As shown in Figs. 1, 4 and 8, the bearing *d* of shaft *c* is provided with an oil supply pipe 44, and is formed adjacent to the recess for the collar 41, with an internal annular oil groove 45, connected by a longitudinal duct 46 in the under side of the bearing 60 with the crank case of the compressor, which is provided with an oil outlet pipe 47. The supply pipe 44 and the outlet pipe 47, will, when practicable, be connected with the lubricating system of the engine to which the 65

starter is applied, the supply pipe 44 being connected with an elevated reservoir, and the outlet pipe with the oil well or receptacle in the crank case of the engine from which the oil is elevated into the reservoir 70 by a pump in the wellknown or any suitable manner.

Referring to Fig. 10, showing a modification of the automatic fluid pressure controller of the compressor, the cylinder *m'* is 75 formed with two chambers 48 and 49 and the toothed plunger *l'* which meshes with the pinion *k* is fitted in the chamber 48 and is connected by a stem 50 passing through an opening in the partition between the 80 chambers with a piston head 51 having a working fit in the chamber 49. Compressed air is admitted to and released from the chamber 49 below the piston head through a passage *r'* formed in the lower cylinder 85 head, and a passage *s'* connects said chamber above the piston head with the storage chamber *u*. The piston head 51 is formed or provided on the upper side with a valve 52, which has a seat in the partition between 90 said chambers around the opening for the stem 50.

In this form of controller the principle of which is the same as that of the other, the packing for the piston head and upper 95 cylinder head is omitted.

In the operation of the apparatus, to start the engine, air at the requisite pressure is admitted by the proper manipulation of the driver's valve from the tank or reservoir 100 through the pipe 8 into the passage 9 in the carbureter cover, from which it freely enters the chamber 25 through the unrestricted port 39, thereby immediately establishing reservoir pressure in said chamber. From 105 the passage 9 the air flows downwardly through the tube 38 into the well 10, thence through the passages 11 and 12 into the upper end of the cylinder or pressure chamber 5 in the distributor casing *z*. When compressed air is admitted to the carbureter the gasoline or other liquid fuel contained in chamber 25 is thereby forced upwardly through the nozzle 27, which discharges it 110 in a spray into passage 9, where it is mixed with the air as it rushes through the passage across the small discharge orifice of the nozzle. In its passage through the well 10 the first air admitted to the carbureter takes up the gasoline in said well, carrying it on 115 through the passages 11 and 12 and the distributing valve, to the engine. The first charge delivered to the engine is thus thoroughly carbureted, thereby insuring the prompt and effective operation of the starting apparatus.

Upon the admission of the compressed mixture into the chamber 5, the piston 22 is instantly shifted downward, uncovering the ports or passages 4 and carrying the cam 16 120

into operative position relative to the stems of the valves y . The valve connected with the cylinder whose piston is on its firing stroke, is opened by this downward movement of the cam, as shown in Fig. 7, and a charge of the compressed carbureted mixture is delivered through the passage 6 and pipe 7 into that cylinder, where it is ignited in the ordinary manner by an electric spark, and imparts an impulse to the piston, thereby starting the engine.

As the engine starts, the driving shaft c is turned, and through its gear connection with the shaft 18, rotates the cam 16, which opens the valves y one after another, thereby admitting the carbureted mixture at igniting pressure to the several cylinders in the proper order on the firing strokes of their pistons.

20 A few impulses being sufficient to start the engine, the supply of compressed air is shut off by the proper manipulation of the driver's valve from the starting apparatus, and the pipe 8 is opened to the atmosphere. 25 As the compressed starting mixture is released from the chamber 5, the spring 24 returns the cam 16 and the piston 22 to their normal positions, thereby closing the ports or passages 4 and permitting all of the 30 valves y to be closed by the springs 3, and to remain closed and inactive during the normal operation of the engine.

When compressed air is released from the carburetor, the chamber 25 is replenished 35 with gasoline or other liquid fuel through the supply pipe 32, the needle valve 34 being closed by the float 26 when the liquid in said chamber reaches the desired level. When the carburetor is charged with compressed air and the float 26 descends, the needle valve 34 will ordinarily be kept closed by the air pressure in the chamber 25, but in case it should not be tightly closed, the check-valve 35 will prevent escape of the air 40 through the passage 29 and the pipe 32, which is ordinarily connected with the tank from which the engine is supplied with fuel.

To charge the air tank or reservoir with compressed air, the driver's valve is turned 50 into position to connect the tank or reservoir with the compressor a through the pipe w . If there is sufficient pressure in the tank or reservoir, compressed air admitted therefrom through the pipe x and passage r into the lower end of the controller cylinder m , will shift the piston or plunger l upward against the packing ring or disk t , thereby forming a fluid tight joint between the upper cylinder head and the upper end of the 55 piston around the cavity therein and the port s . This upward movement of the piston turns the pinions j and k , shifting the clutch member f from the position in which it is shown in Fig. 4 into engagement with 60 the driving shaft c , and the engine being

started, operates the compressor which replenishes the air tank or reservoir through the pipe w . The compressor is thus started by the proper manipulation of the driver's valve. If however, there is insufficient pressure in the tank or reservoir to start the compressor in this way, the clutch member f is shifted into engagement with the driving shaft c by turning the pinion shaft manually with the handle v . When the desired 70 pressure has been reached in the tank or reservoir, the driver's valve is turned into its neutral position to close communication between the compressor and the tank or reservoir and to open the pipe w to exhaust. 80 When the air is thus released from the lower end of the cylinder m , the expansion of the compressed air in the cavity of the piston l and in the storage chamber u connected through the port s with the upper 85 end of the cylinder m , shifts said piston back to its original position, as shown in Figs. 3 and 5. This movement of the piston operates through the pinions j and k to shift the clutch member f out of engagement 90 with the driving shaft c , and thereby stops the compressor. When the piston l is shifted to its upper position by the admission of compressed air into the lower end of the cylinder m to start the compressor, it is positively held in that position as long as the compressed air is confined in the cylinder below the piston by the unbalanced pressure against the lower end of the piston represented by the area between the internal circumference of the cylinder and the rim at the upper end of the piston which is seated against the packing disk t and forms a fluid tight joint therewith. After the piston has been shifted to its upper position, 100 as above stated, compressed air gradually leaks from the lower end of the cylinder m through the restricted passage n into the upper end of the cylinder and the cavity in the piston, and thence through the port or 105 passage s into the storage chamber u , until the pressure in said chamber is equal to reservoir pressure or the pressure in the lower end of said cylinder. After the piston is shifted back to its lower position to stop 110 the compressor as above explained, the compressed air confined in the chamber u and the upper end of the cylinder m , gradually escapes through the leak passage n into the lower end of the cylinder, and thence 115 through the passage r and pipes x and w to the atmosphere at the driver's valve. 120 The operation of the modified form of controller shown in Fig. 10 is essentially the same as the operation of that shown in Figs. 125 3 and 5. When compressed air is admitted through the passage r' into the lower end of the cylinder m' to start the compressor, it acts on the full area of the piston head 51, until the check valve 52 closes the open- 130

ing in the partition through which the stem 50 passes, whereupon the air pressure will continue to act effectively upon an area equal to that of said opening to positively hold the piston head in its upper position as long as the compressed air is confined in the lower end of said cylinder. While it stands in this position, air gradually leaks by the piston head into the space above it and thence through the passage *s'* into the chamber *u*, until the pressures in said chamber and the lower end of the cylinder are balanced. When the piston head is shifted to its lower position to stop the compressor by releasing the air from the lower end of the cylinder, the expansion of the compressed air in the storage chamber *u* acts through the passage *s'* on the upper end of the piston head 51 outside of the check valve, and after the piston head has been shifted to its lower position and the check valve opened, the compressed air confined in the chamber *u*, will gradually leak by the piston head into the lower end of the cylinder and through the opening around the stem above the piston head until the pressure in said chamber is reduced to that of the atmosphere with which it communicates through said restricted passages.

The driving shaft *c*, which runs constantly while the engine is in operation, and the working parts of the compressor with the clutch member and clutch shifting pinions controlling the operation of the compressor, are kept thoroughly lubricated by oil supplied to the bearing *d* through the pipe 44. From the opening of the supply pipe 44 into the bearing *d*, the oil flows in all directions around the driving shaft *c*, clutch member *f* and the adjacent journal of the crank *b*, next to which it drains into the crank case. From the clutch member *f* when it is rotated by the crank shaft, oil is delivered to the pinion *j*, and working along the pinion shaft, lubricates the pinion *k* and the plunger *l* or *l'*. The surplus oil flowing from the supply pipe 44 toward the outer end of the driving shaft *c*, is intercepted by and caught in the groove 45, from which it is conducted through the duct 46 into the crank case. The outlet pipe 47, through which surplus oil overflows from the crank case, is so located that the oil in the crank case is maintained at such a level that the crank *b* when the compressor is in operation, will dip slightly into it and take up enough to properly lubricate the compressor cylinder and piston against which it is thrown by the rapid action of the crank, the outside journal of the crank being supplied by oil taken up and conducted thereto by the crank.

The plunger 22 in its normal position closing the ports 4, as shown in Fig. 6, delays the admission of the compressed starting fluid into the outer ends of the distributing valve chambers until the cam 16 has been

shifted into operative position and has opened one of the valves *y*, as shown in Fig. 7, thus facilitating the preliminary opening of the first valve before the cam begins to rotate.

70

Various modifications in the minor details of construction and arrangement of parts may be made without materially affecting the operation of the apparatus, and without departing from the principle and scope of the invention as defined in the following claims.

75

I claim:

1. In starting apparatus for internal combustion engines, a self-contained unit comprising a distributing valve, a compressor, a carbureter comprising a liquid fuel chamber connected with the distributing valve and having liquid fuel and compressed air supply connections, and a common driving shaft for the distributing valve and compressor.

80

2. In starting apparatus for internal combustion engines, a self-contained unit comprising a compressor, a distributing valve, a carbureter comprising a liquid fuel chamber connected by a passage with the distributing valve chamber and having liquid fuel and compressed air supply connections and automatic means for regulating the supply of fuel to said chamber according to the liquid level therein, and a common driving shaft for the compressor and distributing valve.

85

3. In starting apparatus for internal combustion engines, a self-contained unit comprising a compressor, a distributing valve, a carbureter connected by a passage with the distributing valve chamber, a cam for actuating the distributing valve, a common driving shaft for the compressor and the valve actuating cam, and a fluid pressure actuated clutch adapted to connect and disconnect the compressor and driving shaft.

90

4. In starting apparatus for internal combustion engines, a self-contained unit comprising a distributing valve, a shaft provided with an axially shiftable cam for actuating said valve, a carbureter connected with the distributing valve chamber and having a compressed fluid supply connection, and a fluid pressure actuated member adapted to shift said cam into operative position when compressed fluid is admitted to the carbureter.

100

5. In starting apparatus for internal combustion engines, the combination of a distributing valve, a shaft provided with an axially shiftable cam for actuating said valve, a carbureter connected with the distributing valve chamber and having a compressed fluid supply connection, a fluid pressure actuated member adapted to shift said cam into operative position when compressed fluid is admitted to the carbureter,

105

110

115

120

125

130

and a driving shaft arranged transversely to the cam shaft and connected therewith by gears.

6. In starting apparatus for internal combustion engines the combination of a casing containing a carburetor chamber having a compressed air supply connection; a distributing valve casing mounted on the carburetor casing and containing a valve chamber and a plunger chamber connected by passages with the carburetor chamber and with the valve chamber; a distributing valve controlling the supply of compressed carbureted mixture from the carburetor to the engine; a shaft provided with an axially movable cam for operating the distributing valve; and a plunger fitted in said plunger chamber and adapted when compressed air is admitted to the carburetor chamber, to shift said cam into operative position and to establish communication between the carburetor chamber and the distributing valve chamber.

7. In starting apparatus for internal combustion engines the combination of a distributing valve, a shaft provided with an axially shiftable cam for operating said valve, a carburetor connected with the distributing valve chamber and having a compressed fluid supply connection, a fluid pressure actuated member adapted to shift said cam into operative position when compressed fluid is admitted to the carburetor, a driving shaft connected by gears with the cam shaft, a compressor having a crank shaft in axial alinement with the driving shaft, an axially movable toothed clutch member for operatively connecting said crank shaft with the driving shaft, an inner cased toothed plunger and a shaft provided with pinions meshing with the teeth of said plunger and clutch and adapted to shift said clutch into and out of operative position when compressed fluid is admitted to and released from said plunger.

8. In starting apparatus the combination of a compressor having a crank shaft, a driving shaft in axial alinement with said crank shaft, an axially movable toothed clutch member interposed between proximate ends of said shafts, a casing formed with a piston chamber having a compressed air supply connection, an air storage chamber connected with said piston chamber, a piston head provided with rack teeth and fitted in said piston chamber between its air supply connection and its connection with said storage chamber, and a shaft provided with pinions meshing with said rack teeth and said toothed clutch member.

9. In starting apparatus for internal combustion engines, the combination of a compressor having a shaft, a driving shaft, a clutch member for connecting the compressor shaft with the driving shaft, a casing

formed with a piston chamber having a compressed air supply connection at one end and an opening at the other end, the compressed air storage chamber connected with said piston chamber, a piston head fitted in said piston chamber between its supply connection and its connection with said storage chamber and provided with a valve adapted to close said opening when the piston head is shifted toward it by the admission of compressed air to the piston chamber through its supply connection, and a connection between the piston stem which passes through said opening and said clutch member.

10. In starting apparatus for internal combustion engines, the combination of a liquid fuel chamber, a well having a restricted opening into said chamber below the liquid level therein, a compressed air supply connection opening directly into the upper part of said chamber, a passage leading from said air supply connection over said chamber into said well and having an outlet above the opening from the well into said chamber, and a spray nozzle leading upwardly from said chamber below the liquid level therein into said passage.

11. In starting apparatus for internal combustion engines, the combination of a liquid fuel chamber, a well having a restricted opening into said chamber below the liquid level therein, a compressed air supply connection opening into the upper part of said chamber, a passage leading from said air supply connection over said chamber and opening into said well below the normal liquid level in said chamber, an outlet leading from said well above the opening of said passage into the same, and a spray nozzle leading upwardly from said chamber below the liquid level therein into said passage.

12. In starting apparatus for internal combustion engines the combination of a liquid fuel chamber having a fuel supply connection, a valve controlling the admission of liquid fuel into said chamber, a float adapted to operate said valve and to maintain a substantially constant liquid level in said chamber, a compressed air supply connection opening directly into the upper part of said chamber, a compressed air passage leading from said air supply connection over said chamber, a spray nozzle leading upwardly from said chamber below the liquid level therein into said passage, and means for supplying the carbureted air under pressure to the cylinder of an engine on the firing stroke of the piston.

13. In starting apparatus for internal combustion engines the combination of a liquid fuel chamber having a fuel supply connection provided with an outwardly closing check valve, a regulating valve con-

trolling the admission of liquid fuel into said chamber, a float adapted to operate said valve and to maintain a substantially constant liquid level in said chamber, a compressed air supply connection opening directly into the upper part of said chamber, a restricted compressed air passage leading from said air supply connection over said chamber, a spray nozzle leading upwardly from said chamber below the liquid level therein and opening into said passage, and means for supplying the carbureted air under pressure to the cylinder of an engine on the firing stroke of the piston.

14. In starting apparatus for internal combustion engines the combination of a bearing sleeve formed adjacent to one end with an internal annular oil groove and provided with an oil supply connection, a driving shaft rotatably fitted in said sleeve, a crank case into which said sleeve opens at the end opposite said oil groove, a crank shaft having bearings in said sleeve and case coaxial with the driving shaft, an oil outlet connection leading from said crank case, a clutch member inclosed in said bearing sleeve between said shafts and adapted to connect and disconnect the same, and an oil duct leading from said groove along

the under side of said bearing sleeve into said crank case.

15. In starting apparatus for internal combustion engines, the combination with a compressor having a crank case provided with an oil outlet connection and a cylinder mounted upon and opening at its lower end into said case; of a casing having a bearing sleeve opening at one end into said crank case above said outlet connection and provided with an oil supply connection and a transverse bearing sleeve intersecting the upper part of the other bearing sleeve, a crank having bearings in said first mentioned bearing sleeve and crank case coaxial with said driving shaft, an axially movable toothed clutch member rotatably fitted in said sleeve between the driving shaft and the adjacent crank journal and adapted to detachably connect said shaft and crank, and a shaft mounted in said transverse bearing sleeve and provided with a pinion meshing with said clutch member.

In witness whereof I hereto affix my signature in presence of two witnesses.

NIELS A. CHRISTENSEN.
